GAME SCORING DEVICE

Benjamin de C. Rothschild, Coral Gables, Fla.

Application January 26, 1939, Serial No. 252,980

1 Claim. (Cl. 273—136)

The present invention relates to an improved game tally which is combined with a card table in a novel manner.

The primary object of my invention is to provide, in combination with a card table, an improved device for keeping the score of the game being played.

A further object of my invention is to provide, in combination with a card table, a game tally in the form of a continuous strip of paper the ends of which are wound upon rolls or spools and having a portion of the strip intermediate the two spools exposed to view on the top of the card table.

A further object of my invention is to provide easily accessible means for rotating either of the spools in order to advance the score tally to provide a new and unused portion of the strip for score keeping or to turn back the tally for the purpose of referring to the score of a previous game.

A still further object of my invention is to provide a score tally which, although exposed at the top of the card table, will afford no inconvenience and will not interfere in any way with the dealing or playing of the cards.

Another object of my invention is to permit a reduction in the cost of game tallies by providing for their manufacture and sale in continuous strips conveniently wound on rolls or spools.

A still further object of my invention is to provide such a device which can be manufactured at low cost and which can be added to card tables without materially increasing the cost thereof.

Other objects are obvious or will become apparent during the following description of the device.

An understanding of the details of my invention may be had from the following description with reference to the accompanying drawing wherein:

Figure 1 is a top plan view of a card table showing two of my score tally devices attached thereto;

Figure 2 is a sectional view taken along the line 2—2 of Figure 1;

Figure 3 is a top plan view of the device for holding the tally strip spool and showing it detached from the table; and

Figure 4 is a sectional view taken along the line 4—4 of Figure 2.

In the drawing, like reference characters are

used to designate like parts in each of the views. The reference numeral 5 generally designates a card table having a top or playing surface 6 and conventional folding legs which for simplicity are not shown in the drawing. The table 5 top 6 has a framework 7 attached to the lower surface of the edges thereof.

Since all of the tally devices are similar, only one will be described in detail. It will be understood that a card table may be provided with 10 one, two or four of the devices if desired.

As best shown in Figure 2, the table top 6 is provided with two parallel spaced slits 8 at each corner of the table where it is desired to provide a score tally. The rectangular shaped area of 15 the table top between the parallel slits is indented or depressed as shown at 9. This depression may be made by stamping or in any other suitable manner.

One end of a continuous strip of score tally 20 indicated by the reference character 10 is inserted from the bottom of the table through one of the slits 8 over the depressed area 9 and downward through the other slit 8. The ends of the tally strip are wound upon spools or rolls 11 25 which are retained in parallel relation to the slits 8.

In order to hold the spools 11 in their proper position, I provide a member, indicated generally 30 by the reference character 12, which is preferably formed of stamped sheet metal. The member 12 is provided with a plane surface 13 having, at the four corners thereof, depending projections 14, 15, 16 and 17. The plane surface 13 is secured to the lower side of the depressed area 9 by means of screws 18 or by any other suitable means. The depending projections 14 and 15 are provided with short stud-like bearing members 19 35 near their lower ends. The depending projections 16 and 17 extend outwardly and downwardly as shown in Figures 3 and 4 and have holes 20 near their lower ends.

The spools or rolls for holding the strip of score tally are designated by the reference character 11. 45 One end of each spool is provided with a cavity 22 into which the bearing member 19 is adapted to be inserted. The opposite end of each spool is provided with a cavity of angular cross-section and is designated by the reference character 23. 50 Holes 24 are drilled in the framework 7 in such positions as to coincide with the holes 20 in the depending projections 16 and 17. Shafts 25 are inserted through the holes in the framework 7 and the depending projections 16 and 17 and in- 55

to the cavities 23 in the spools 11. The shafts 25 have inner ends of angular cross-section as indicated by the reference character 26 in Figure 4 and are adapted to fit into the cavities 23 in 5 the spools 11. The outer ends of the shafts 25 are provided with knurled knobs 27 which are secured to the shafts to prevent rotation thereon. Around the shafts 25 and between the spools 11 and the depending projections 16 and 17, I 10 provide compressible helical springs 28.

The operation and use of my device is very simple. A spool 11 having wound thereon a continuous strip of score tallies is inserted between the depending projections 14 and 16. The free 15 end of the strip of score tallies 10 is partially unwound from the spool 11 and is inserted through the adjacent slit 8, over the depressed area 9 and downward through the other slit 8 and is partially wound around the opposite spool 11. That 20 portion of the score tally 10 which is then exposed on the table top is in position for use. Because of the depressed area 9 the exposed portion of the score strip 10 will lie flush with the table top and will therefore not interfere with dealers or 25 other players.

When the exposed portion of the tally strip 10 is filled, the right hand knob 27 (Figure 3) may be rotated to reel the exposed portion onto the right hand spool 11 and to expose an unused portion 30 of the tally strip 10 on the table top. In case it is desired to refer back to the score of a previous game, the left hand knob may be rotated to re-expose the previously used portion of the tally strip. When the spools 11 are in position the 35 40 helical springs 28 will be slightly compressed, thereby providing limited frictional opposition to rotation of the spools which enables the tally strip 10 to be held snugly against the depressed area 9 and prevents unintentional rotation of the spools.

It will be seen that I have provided a device for use in keeping the score of card games which is extremely simple and convenient in use and

which is of such simple and inexpensive design that it can be attached to card tables without materially increasing the cost thereof.

While I have shown and described my invention in some detail it will be obvious that various 5 modifications may be used without departing from the scope of my invention as defined in the following claim.

Having thus described the invention, I claim:

In combination, a card table top comprising 10 a continuous unitary sheet of material forming a playing surface, a pair of spaced parallel slits extending through said sheet, the rectangular shaped area of said sheet lying between said slits being depressed below the normal level of the remainder of said playing surface, a metal plate secured beneath and substantially coinciding with said depressed rectangular shaped area, projections integral with and depending from each corner of said plate, the projections depending 15 from one side of said plate being provided at their lower ends with stud like bearing members, the projections depending from the opposite side of said plate having an aperture at their lower ends, parallel shafts extending from beyond the edge of 20 said playing surface through said apertures, the inner ends of said shafts being of angular cross-section, a pair of spools each rotatably supported at one end by one of said stud like bearing members and being supported at their opposite ends 25 by the angular ends of said shafts which are inserted into cavities of corresponding angular cross-section in said spools, compression springs surrounding said shafts and compressed between the ends of said spools and the adjacent depending 30 35 40 projections, and a strip of score tallies adapted to be wound upon said spools and to extend through said slits in such manner as to occupy the depressed rectangular area on said playing surface to thereby permit progressive movement of said score tallies by rotation of either of said shafts.

BENJAMIN DE C. ROTHSCHILD.
